- (57) **CLAIM**
The ornamental design for a radio frequency aperture as shown and described.

DESCRIPTION

FIG. 1 is a first perspective view of the radio frequency aperture with the case affixed; and, FIG. 2 is a second perspective view of the radio frequency aperture with the case removed. The dash-dash broken lines shown in the drawings illustrate portions of the radio frequency aperture that form no part of the claimed design. The dot-dash-dot broken lines indicate environmental portions of the structure, and form no part of the claimed design.
